UNITED STATES PATENT OFFICE.

WILLIAM JAMES LILLY, OF BUTTE, MONTANA.

HOISTING-ENGINE CONTROL.

1,314,675.

Specification of Letters Patent. Patented Sept. 2, 1919.

Application filed May 16, 1917. Serial No. 169,150.

To all whom it may concern:

Be it known that I, WILLIAM J. LILLY, a subject of the King of Great Britain, residing at Butte, in the county of Silver Bow 5 and State of Montana, have invented a new and Improved Hoisting-Engine Control, of which the following is a full, clear, and exact description.

My invention relates to the control of 10 hoisting engines and parts associated therewith, my purpose being to prevent overspeeding of the hoisting mechanism carrying the skip or cage, also the prevention of hoisting the cage beyond a predetermined 15 point at the top, or lowering it into the sump at the bottom.

More particularly stated, my invention comprehends improved mechanism, controllable by the speed of the hoisting mechanism, for shutting off the power of the hoisting engine and for applying the brake mechanism.

My invention further comprehends mechanism, controllable partly by the speed of 25 the hoisting mechanism and partly by the relative positions assumed by various movable parts for stopping the hoisting engine and applying the brake mechanism in the event that the operator fails to check the 30 speed of the hoisting mechanism when the skip or cage reaches the proximate end of its trip either upward or downward.

Reference is made to the accompanying drawings forming a part of this specification, and in which like letters indicate like parts.

Figure 1 is a side view, partly in elevation and partly diagrammatic, showing my device used in connection with a hoisting engine and brake mechanism associated therewith;

Figs. 2 and 3 are respectively front and rear views of the mechanism for throwing the tripping device into action when the hoisting engine is overspeeding or overwinding; also for giving the alarm when the engine is beginning to overspeed or overwind, and for giving the engineer the signal when the cage or skip is nearing the landing on the surface or at the bottom of the shaft; also for regulating the speed of the brake control mechanism;

Fig. 4 is a detail view, in side elevation, of Fig. 2;

Fig. 5 is a detail view of the electrical make and break device;

Fig. 6 is a sectional view on the line 6—6, Fig. 2;

Fig. 7 is a perspective view of the tripping mechanism for operating the throttle 60 and brake;

Fig. 8 is an elevation of the mechanism for producing instant action on the brakes and throttle of hoist in case the cages or skips are carried beyond the limits of safety 65 at the top of head frame; and

Fig. 9 is a detail view of part of the tripping mechanism.

The hoisting engine cylinder is shown at 4, the throttle valve at 5, the throttle 70 mechanism at 6, and the throttle shaft at 7. Mounted rigidly upon this throttle shaft is an arm 8. An actuating bar 9 is provided at one of its ends with a link 10, the latter fitting slidably upon a pin 11 carried by 75 the arm 8. When the actuating bar 9 is moved obliquely downward in the general direction of its length, the throttle mechanism is actuated and the engine is stopped.

Various parts of the engine are shown at 80 12, and at 13 is a connecting rod for actuating the throttle mechanism independently of the actuating bar 9. A lever 14 is disposed adjacent a platform 15, serving as the engineer's stand, and the lever 14 is connected with the rod 13.

The brake drum, forming a part of the hoisting mechanism, is shown at 16. The brake shoes appear at 17, and connected with them are brake levers 18. The brake 90 shoes are supported upon rocking arms 19, having the usual or any preferred form. Connected with the brake levers 18 are rods 20, which are also connected to a lever 21 which is journaled upon a pedestal 22. Pivotally connected to the lever 21 is connecting rod 23. The latter being also connected by a pivot 24 with the sliding head of a brake engine 25. This brake engine may be substantially of the usual or any desired 100 construction.

The brake drum 16 is provided with gearing 26, the latter being connected with a revoluble shaft 27, this shaft being connected by gearing 28 with a countershaft 29^a, commonly used for operating the engine indicator, and mounted rigidly upon this counter-shaft 29^a is a sprocket wheel 30, carrying a sprocket chain 30^a, which operates through the sprocket wheel 31 to operate the governor 40, disks 45 and 43 and the contacts of the control mechanism.

On the shaft 29, Fig. 2, is mounted a worm 33, meshing with a worm wheel 35 on the shaft 44 that carries and revolves a disk 45 in a clockwise and contra-clockwise direction in unison with the hoisting drum on the engine. Mounted also upon the shaft 29 is a gear 36, which meshes with a pinion 37, which is mounted on the shaft 37^a, on the other end of which is a gear 38, that meshes 10 with a gear 39 which revolves the fly balls 40 of the governor on the top of stand 42. The governor ball arms engage at 40^c the upper end of a sliding rod 41, adapted to play vertically. The bottom of the rod 41 rests in a step bearing 41^a on the upper 15 end of a rod 41^b, which slides up and down vertically in proportion to the rising and lowering of the fly balls 40 of the governor. The step bearing 41^a is recessed at 41^c to 20 accommodate the end of a lever 57 which is mounted rigidly on a shaft 55; said lever 57 having at its extremity a weight 57^b.

An oil dash pot 57^c is supported by means of a bracket 57^e, which is adjustably attached to side of stand 42. A piston rod 57^a is connected to the lever 57 by means of a pin 57^e. On the lower end of the piston rod is a piston 57^c, and underneath the piston is a spiral spring 57^d. The object of the dash-pot is to eliminate shock and irregularity caused by the pulsation of a heavily loaded engine. The spring underneath the piston increases the range of operation of the governor, producing quicker action on starting 35 a load by means of the spring assisting in the raising of the weight 57^b, and increasing the range of action of governor when slowing down the engine by retarding the dropping of weight.

40 On the shaft 55 is also mounted an arm 56, which carries contacts 52 and 53, which are mounted on springs 52^a and 53^a, which are secured to the arm 56 by means of a bolt 52^b. An arm 50 is loosely mounted on 45 a pin 54, and on the side of the arm is attached a roller 49, and on the end of the arm is a contact 51.

Electric wires 51^c, 52^c and 53^c are connected to the contacts 51, 52 and 53, respectively. These wires are extended to connect with the bell 67, battery 68 and coil 69, as shown in Fig. 1.

On the inside face of disk 45 is adjustably mounted a cam 58. On the outside face of the disk are slidably mounted cams 46 and 46^a by means of bolts 47 and 47^a which are slidable in the groove 48. Pivotally mounted on one of the bearing boxes 34 for the shaft 29, by means of pin 59^b, is a bell crank lever 59, one end 59^a of which is so positioned that it is in line with the path of travel of the cam 58, while on the other end is pivoted at 59^c a lever 60, which has its upper end connected with the arm 50 by means of a 65 connecting rod 63. The lower end of the

lever 60 has a bevel projection 60^a which is positioned in the path of travel of a cam 62, which is attached to the hub of the gear 36 by means of a screw 66. A spring 61 is connected with the lever 60 and the lever 59 70 so as to keep them in correct position relative to each other.

The shaft 44, which extends entirely through stand 42, has mounted upon it the disk 45, the worm wheel 35 and the disk 43. 75 Mounted slidably on the face of the disk 43 are spaced cams 77 and 77' which are used for the purpose of operating brake lever stop 81, Fig. 7. On the rim of the disk 43 is a trip 70, which is secured to the rim of 80 disk by means of the screw 70^a, and is so positioned that when the skip or cage is at a predetermined distance from the top landing the circuit between the wires 74 and 75 is closed by means of the trip 70 coming in 85 contact with the pin 71 and forcing the spring 72 in contact with 73, which causes the bell 67 to ring to notify the engineer for slowing down the engine for the top landing.

Fig. 7 represents the weight and tripping mechanism for operating the throttle and the brakes of hoist. Mounted rigidly upon the shaft 93 is an arm 104, and this arm carries a weight 101 for turning the shaft 93. The arm 104 is connected with a dash-pot 102, for preventing unduly rapid or jerky movement of the arms and valves. On one end of the shaft 93 is securely mounted an arm 108, to which is connected the rod 9 100 for operating the throttle valve, and on the other end are arms 82 and 83 for operating the brake engine mechanism. The arm 82 is loosely mounted on the shaft and is supported by a projection 83^a on the lever 83, 105 which is rigidly mounted on the shaft 93. Mounted on the lever 82 is a rod 84^a having a spring 84 for giving tension between the lever 82 and a lug 83^b on the lever 83, for the purpose of operating the brake engine 110 valve. Near the end of the lever 82 is connected a rod 86 by means of a pin 86^a, and at the top of the rod 86 a loop is provided for the purpose of permitting free movement of the arm 91 when the engineer is 115 operating the brake. A latch 88 is connected to the upper part of the loop for the purpose of latching the pin 90 when the weight 101 is released and the loop pulls down on the pin 90, thus preventing the pin 120 from being jerked beyond the point determined for the proper operation of the brake. A rod 92 is connected to the latch 88 and extends through the projection 83^a, having a spring 87 and nuts at the bottom for the adjustment of the latch 88. On the end of the arm 82 is a projection 82^a which extends downward for the purpose of resting on stop 81. The shaft 93 is also provided with a spring 105, which may be used for the pur- 125 130

pose of producing tension to the shaft in place of the weight 101, or may be used in connection with the weight for increasing the tension when desired. The weight 101 is supported by means of a lever 100, which is pivoted to the standard 99 by means of a pin 100^a. At the other end of the lever 100 is a lug 100^b which projects underneath a lever 98, and in turn is held in place by means of a latch 97. Connected to the latch near its upper end is a link 96, to which is connected the end of lever 95^a. The lower end of this bell crank lever is placed in line with the plunger 94 of an electric coil 69, which is designed for the purpose of tripping the latch 97 when the control mechanism is brought into action for stopping the engine.

Fig. 8 represents a supplementary device which may be placed on the head frame, directly under the sheaves, for the purpose of shutting the throttle and applying the brakes in case the cages are hoisted to a point of danger beyond that for which the control mechanism is set, which may occur where the head room is limited and where the variation in the winding of rope on the drum, caused by hoisting a heavy load and hoisting without load, may be greater than the space between the top of cage and the sheave. This supplementary device consists of bell-crank levers 111, rod 114 for connecting from the bell crank levers to cross bar 117 at the top, under which is a spring for holding the bell crank levers 111 in position. On one end of the cross bar is a contact 119, while on the other end is a guide rod 115 for keeping bar in line. Underneath the contact 119 is an adjustable contact 120, having a spring 118 for keeping contact in proper position.

The operation of my device is as follows:

The parts being assembled and arranged as described, the engineer starts up the hoisting engine to raise or lower the load, consisting, say, of a skip or cage. If the load is to be hoisted, the movement of the revoluble parts is such that the disk 45 turns in a contra-clockwise direction, and when the engine is operated at normal speed, the speed of the governor forces the stem 41 downward, which, by means of lever 57, shaft 55 and arm 56, brings the contact 52 down in close proximity to the contact 51. In case the engine increases speed beyond the normal speed, the rising of the governor balls brings the contacts 52 and 51 together, thus closing circuit between the electric wires 51^c and 52^c, which causes the bell 67, in Fig. 1, to ring the alarm for overspeeding, thus giving the engineer an opportunity for reducing the speed of engine to normal. In case, however, the engine is allowed to slightly increase its speed after ringing the alarm, the increased speed of the governor forces the

contact 53 down against the top of the contact 52, which closes circuit between electric wires 53^c and 51^c, and connect with the battery 68 and electric coil 69 shown in Fig. 1, thus causing the plunger 94 to strike the lever 95, which in turn, by means of toggle action of lever 95^a and link 96, forces the latch 97 from the end of the lever 98 and thereby releases the lever 100 and permits the weight 101 to drop. When the weight 101 drops, the throttle valve is instantly closed by means of the arm 108 and rod 9. The dropping of weight also forces the lever 82 downward, by means of the set screw 85 and spring 84, until the lug 82^a rests on the top 80 of the stop 81, which by means of the rod 86 and loop 89 pulls down on the pin 90, which sets the brake of the hoisting engine and stops the engine. When the loop 89 comes in contact with the pin 90, the latch 88 is in 85 position to be thrust underneath the pin 90, which is accomplished by the lever end 82^a coming in contact with the stop 81, when lever support 83^a continues its downward course until the set screw 85 rests on the top 90 of the lever 82, which action throws the latch 88 under the pin to prevent it being carried too far by the momentum of the downward stroke. In ordinary performances of hoisting, when the cage or skip is within a certain 95 predetermined distance from the top landing, the cam 70, in Fig. 3, comes in contact with 71, which closes the circuit between electric wires 74 and 75, and causes bell 67, in Fig. 1, to ring, thus notifying the engineer 100 when it is time to slow down the engine. In case the engineer fails to reduce the speed of engine, the cam 46, in Fig. 2, which is secured to the rim of the disk 45, travels under the roller 49, and carries contact 51 upward until it closes the circuit between contacts 51 and 52, causing the bell 67 to ring the alarm for the engineer to slow down the engine. In case the engineer does not immediately respond, a contact is made 110 between 52 and 53, which closes the circuit between electric wires 51^c and 53^c and instantly releases the weight 101 by means of the coil 69, which closes throttle valve and sets the brake.

In case the engineer slows down the speed of the engine on approaching the top landing, then as the cam 46 passes under the roller 49, which raises the contact 51, the slowing down of the governor gradually 120 draws the contact 52 upward away from the contact 51 so that the control is not called into service to stop the hoist in the slowing down process if the work is properly done by the engineer. If, however, the engineer 125 fails to perform the process of slowing down the engine and stopping at the landing in proper manner, the cam 46 continues to raise the contact 51 until it strikes 52, which closes circuit and rings the alarm, and in 130

case the engineer does not immediately respond, the circuit between 52 and 53 is closed and the weight 101 is instantly released by means of the coil 69, and the 5 throttle is closed and the brake set, which stops the engine.

When the cage is within a short distance of the top landing, the cam 58, which is attached to the rear of rim of the disk 45, 10 comes in contact with projection 59^a on the lever 59, which carries the projection 60^a forward in the path of travel of the trip 62, so adjusted that when the cage is hoisted to the point of landing, the trip is in close 15 proximity to the projection 60^a. In case the cage is carried a few inches beyond the pre-determined limit of travel, or in case the engineer fails to reverse the engine after making a landing and moves the engine in the 20 wrong direction, the cam 62 on account of its high speed, instantly strikes the projection 60^a on the lever 60, which is pivoted at 59^c, and by means of the connecting rod 63 and lever 64, instantly closes the circuit between 25 the contacts 51, 52 and 53, which causes the release of the weight 101, that closes the throttle valve, sets the brake and stops the engine.

This high speed trip is very desirable 30 where the distance is limited between the cage and the sheave when the cage is at the upper landing.

The same high speed tripping mechanism may be used for the bottom if it is desired, 35 by attaching a cam to the disk for the bottom landing similar to the cam 58.

The variable speed mechanism for the brake system, shown in Fig. 3, is adapted for all engines of high speed, where it is 40 dangerous to apply the brakes suddenly when the engine is running at its highest speed. When the hoist is running and cage or skip is traveling between the points where the slowing down process begins for 45 the top and bottom landings, the roller 78 is in contact with the face of projection 43^a, as shown in Fig. 3, which, by means of the lever 79 and rod 80, holds the stop 81 in an upright position, as shown in Fig. 7. In 50 case of overspeeding of the hoist while the stop 81 is in this position, the tripping of the weight 101 forces the projection 82^a of the lever 82 down upon the top of the stop 81, in which position the loop 89 pulls the brake 55 engine valve lever downward sufficiently to apply brake gradually, so as to avoid shock or jar to the engine, or to men on cage in the shaft. When the cage is nearing the end of trip, where the slowing down process begins, the cams 77 are so adjusted that the roller 78 comes in contact with the cam, which forces the roller downward, which 60 in turn swings the stop 81 back so that in case the engine is not stopped at the proper 65 place for making the landing and the con-

trolling mechanism is brought into requisition, the weight 101 is tripped and the lever 82 is forced down until the projection 82^a rests at the bottom of notches 81^a, which opens brake valve to its widest angle by 70 means of the loop 89 pulling down the lever 91, which causes the brake to be applied at its quickest speed, stopping the engine in the shortest possible time. Thus it will be seen that in direct inverted ratio to 75 the slowing down of the hoist is the movement of the mechanism for increasing the speed of the brakes, making it impossible to apply brakes suddenly when engine is running at high speed, and as the speed of hoist 80 is reduced the stop 81 is gradually swung back so that in case the engine is not slowed down within the limits of safety, the weight 101 is tripped by the closing of the circuits between contacts 51, 52 and 53, which causes 85 the lever projection 82^a to drop on the notches 81^a, which produces variable speed in the application of brake in proportion to the drop of the lever 82.

A supplementary device is shown in Fig. 90 8, which represents a dead-line trip for attaching to the head frame, directly underneath the sheave. This appliance is desirable in cases where there is great variation in the winding of rope on drum of hoisting 95 engine on account of great depth of shaft, wherein there is a difference of several feet in the position of cage, with relation to the mark on drum, or indicator, in the winding of rope with a heavy load and winding 100 without load, and where the distance between the cage and the sheave is very limited when the cage is at its landing on the top.

This appliance is rigidly attached to the head frame so that in case the cage or skip 105 travels too close to the sheave for safety when winding without load to a mark on drum, the safety dogs 110, with which all cages are supposed to be equipped, strikes the projecting lever 111, which by means of 110 bell crank 111^a and connecting rod 114, pulls down on the bar 117 and closes circuit between the contacts 119 and 120, and by means of the wires 121 and 122, which are connected to the battery 68 and coil 69, shuts 115 off the power and applies brake, as previously explained, which instantly stops engine.

When the controlling mechanism has performed its function in stopping the engine, 120 the weight 101, in Fig. 7, is raised and latched, as before, when it is again ready for action.

Having thus described my invention, I claim as new and desire to secure by Letters 125 Patent:

1. A device of the class described including a governor, a throttle mechanism, a brake mechanism, a contact movable by the governor, a movable element, driving means 130

for the governor and the element, a second contact operated by the said element, and electrical means controlled by the contacts for controlling the throttle and brake mechanisms when the speed of the governor exceeds a certain point and when the said element overtravels.

2. A device of the class described including a governor, a throttle mechanism, a 10 brake mechanism, a contact movable by the governor, a movable element, driving means for the governor and the element, a second contact operated by the said element, electrical means controlled by the contacts for 15 controlling the throttle and brake mechanisms when the speed of the governor exceeds a certain point and when the said element overtravels, a contact intermediate the first-mentioned contacts and movable with 20 one of the same to engage the other contact, and an electrical signal device energized when the intermediate contact engages its companion contact.

3. In an apparatus of the class described, 25 the combination of an engine, a throttle mechanism for the engine, a governor driven thereby, an element also driven by the engine, and separately actuated contacts 1 being actuated by the governor and the other 30 by the said element for controlling the throttle mechanism.

4. In an apparatus of the class described, the combination of an engine, a throttle 35 mechanism for the engine, a governor driven thereby, an element also driven by the engine, electrical means actuated by the governor or by the said element for controlling the throttle mechanism, and electrical means controlled by the governor or said element 40 for sounding a signal before the first-mentioned electrical means becomes operative.

5. The combination of a prime mover, a controller therefor, a governor driven by the prime mover, an element movable by the 45 prime mover, relatively movable contacts controlled by the governor, electrical means energized when the contacts reach closed-circuit position for operating the controller to stop the prime mover, and separate adjustable members on the said element for operating the movable contact when the element reaches the limit of its movement in either direction.

6. In an apparatus of the class described, 55 the combination of a prime mover, stop means therefor, a governor driven by the prime mover, an element driven by the prime mover in either direction, a lever moved by the element and whose movement is controlled by the governor, contacts actuated 60 by the lever, and electrical means for operating the stop means when the contacts engage.

7. In an apparatus of the class described, 65 the combination of a prime mover, stop

means therefor, a governor driven by the prime mover, an element driven by the prime mover in either direction, a lever moved by the element and whose movement is controlled by the governor, contacts actuated by 70 the levers, electrical means for operating the stop means when the contacts engage, a third contact arranged between the first-mentioned contacts and mounted on the said lever and normally insulated from the contact thereof, and a signal circuit controlled by the engagement of the third contact with one of the other contacts, whereby a signal will be given before the stop means is operated. 80

8. The combination of a prime mover, stop means therefor, a rotary element movable in opposite directions by the prime mover, adjustable cams thereon, a movable member operated by either cam, contacts engaged and disengaged by the movement of the member, and electrical means controlled by the contacts for operating the stop means. 85

9. The combination of a prime mover, stop means therefor, a rotary element movable in opposite directions by the prime mover, adjustable cams thereon, a movable member operated by either cam, contacts engaged and disengaged by the movement of the member, a second member, contacts on 90 the members, a governor operatively connected with the second member and driven by the prime mover, said members being normally separated from each other, electrical contacts on the members, and electrical 95 means energized by the contacts engaging to operate the stop means.

10. The combination of a cage-hoisting prime mover, a stop means therefor, a circuit make and break device including a movable member, electrical means controlled by the device for operating the stop means, an element movable with the prime mover, devices on the element for operating the make and break device at the end of the cage 100 travel in either direction, and means for operating the make and break device in case of over-speeding of the cage. 105

11. The combination of a cage-hoisting prime mover, a stop means therefor, an electrical means for operating the stop means, a governor connected with the prime mover, an element rotatable in either direction by the prime mover, a weighted lever connected with the governor, an arm connected with 115 the lever, a second arm, contacts on the arms for controlling the circuit of the electrical means, and means on the said element for actuating the last-mentioned arm. 120

12. The combination of a cage-hoisting prime mover, stop means therefor including a brake and throttle device, an electrical means for operating the stop means, a governor including a rotatable member, a second member engaged with and reciprocated by 125 130

- the first member, a lever connected with the second member, and a make and break device actuated by the lever for controlling the electrical means.
13. The combination of a cage-hoisting prime mover, stop means therefor, a governor, a make and break device having relatively movable contacts, means for moving one of the contacts by the governor, an electrical means controlled by the make and break device for operating the stop means, an element movable with the cage, a cam carried by the element, a lever actuated by the cam, a second element operating simultaneously with the cage, and means actuated by the lever for actuation by the second element to operate the other contact of the make and break device than the one connected with the governor.
14. The combination of a cage-hoisting prime mover, an electrically operated stop means therefor, a make and break device for controlling the stop means, an element movable simultaneously with the cage, a cam on the element, a lever arranged to be actuated by the cam, a second element, a cam on the second element, a second lever connected with the first and adapted to be actuated by the second cam, and means for connecting the second lever with the make and break device to actuate the same.
15. The combination of a cage hoisting prime mover, electrically operated stop means therefor, a governor, a make and break device for the stop means and operated by separate agencies, one agency including a governor and the other agency comprising the following: an element movable simultaneously with the cage, a cam on the element, a second element movable with the cage, a cam thereon, and means moved by the first cam into the path of the second cam and connected with the make and break device for actuating the same.
16. The combination of a cage hoisting prime mover, electrically operated stop means therefor, a governor, a make and break device for the stop means and operated by separate agencies, one agency including a governor and the other agency comprising the following: an element movable simultaneously with the cage, a cam on the element, a second element movable with the cage, a cam thereon, a lever actuated by the first cam, a second lever mounted on the first lever and moved thereby into the path of the second cam, spring means between the levers for holding the second lever yielding in a predetermined position, and a connection between the second lever and the make and break device for operating the latter.
17. The combination of a cage-hoisting

engine, a throttle therefor, a brake, and an automatic mechanism for operating the 65 brake and throttle, said mechanism comprising a weighted element, a device for normally holding the same in running position, electrical means for releasing the device, means dependent upon the speed or point of 70 travel of the cage to operate the electrical means, and means controlling the operation of the brake by the weighted element to act gradually or suddenly.

18. The combination of a cage-hoisting 75 prime mover, a brake, a weighted element tending to operate the brake, an arm movable with the element, an adjustable stop for engagement by the arm for controlling the gradual or sudden operation of the brake, 80 said brake including a lever, a member connected with the arm, a slot and pin connection between the member and brake lever, a pivoted device on the loop of the member to engage the pin, and a rod connected with the 85 device and yieldingly connected with the said arm.

19. The combination of a cage-hoisting prime mover, a brake, a weighted element tending to operate the brake, an arm movable with the element, an adjustable stop for engagement by the arm for controlling the gradual or sudden operation of the brake, 90 said brake including a lever, a member connected with the arm, a slot and pin connection between the member and brake lever, a pivoted device on the loop of the member to engage the pin, a second arm rigidly connected with the weighted element, the first-mentioned arm being movably connected 100 with the said weighted element, said rod being connected with the first-mentioned arm through the second-mentioned arm, cushioning means between the arms, and an adjustable member on the second arm for 105 engaging the first-mentioned arm.

20. In an apparatus of the class described, the combination of a weighted element, a shaft to which the element is connected, a throttle mechanism connected with the shaft, 110 a device for holding the element raised, electrically operated means for releasing the device to permit the element to drop, fixed and loose arms on the shaft, members on the fixed arm to engage and move the loose arm, 115 spring means between the arms, a rod connected with the loose arm and having a loop, a brake-controlling lever having a pin engaging in the loop, a pivoted member on the loop, a rod connected with the member and yieldingly connected with the loose arm, and means for varying the movement of the loose arm under the action of the weighted element to variably operate the brake-controlling lever.

WILLIAM JAMES LILLY.
